UNITED STATES PATENT OFFICE.

FRANK SHORT, OF PENN YAN, NEW YORK.

TOY AEROPLANE

Application filed March 13, 1923. Serial No. 624,744.

To all whom it may concern:

Be it known that I, FRANK SHORT, a citizen of the United States, residing at Penn Yan, in the county of Yates and State of New York, have invented certain new and useful Improvements in Toy Aeroplanes, of which the following is a specification.

This invention relates to methods of manufacturing toy aeroplanes or gliders and the resulting article, and resides in certain operative steps and details of construction giving strength and a favorable weight distribution, and simplifying the manufacture.

The construction is such that the stock may be prepared in a continuous strip from which successive blanks are punched. These blanks are then so shaped in dies as to have considerable mechanical strength and at the same time a highly desirable form from the standpoint of successful flight.

The form and the manner of constructing the device are illustrated in the accompanying drawings, in which:

Fig. 1 is a plan view of the complete glider in the preferred form.

Fig. 2 is a side elevation thereof.

Fig. 3 is a front elevation thereof.

Fig. 4 is an enlarged section on the line 4-4 of Fig. 1.

Fig. 5 is an enlarged section on the line 5-5 of Fig. 1.

Fig. 6 is a fragmentary vertical axial section at the nose of the plane.

Fig. 7 is a perspective view of the metal stamping used to stiffen the nose.

Fig. 8 is a view of a portion of the blank strip with the pattern or development of one glider indicated thereon.

Fig. 9 is a plan view of a modified construction in which a cover sheet is used to stiffen the fuselage and wings and close the top of the fuselage.

Fig. 10 is a section on the line 10-10 of Fig. 9.

The method of manufacturing and the structure of the glider may best be understood from a consideration of the blank from which it is formed. This blank is cut from laminated sheet material which preferably is prepared in strip form. It consists in the preferred form of a base strip 15 and a narrower top strip 16 and certain intervening still narrower strips positioned to give the desired graduated thickness. These strips may be of any suitable sheet

material and some of them may even be thin metal or foil, but I prefer paper and shall hereafter refer to paper as the typical material in this description.

In the example chosen for illustration, there are three intervening strips 17, 18 and 19 of successively increasing widths, each adjacent that margin of the strip which forms the forward ends of the blanks, and one strip 20 at the forward edges of the tail surfaces or elevators. More or fewer might be used and their relative locations will be varied somewhat, depending on the size of the glider, the character of the sheet material used and the desired location of the points of maximum thickness. It is not even essential that the various laminae be of uniform thickness.

The blank strip is preferably made up with adhesive and the blanks are preferably punched out and die-pressed to form when the adhesive is partially but not completely dried. Hot dies may be used to set the adhesive if desired. Alternatively the adhesive might be of the type which is softened by heat and the dies might be heated during the forming operation and then chilled to set the article. These general methods are known and are not a feature of the invention, but are mentioned in the interests of a full disclosure.

Each blank is, as shown in Fig. 8, symmetrical with respect to a line perpendicular to the length of the strip 15 and includes a fuselage portion 21, wing portions 22, elevators 23 and two rudder portions 24, which, in the finished glider, are preferably, but not necessarily, glued together to form a single rudder. The reference numerals 21 to 24 used above to describe parts of the blank in Fig. 8 are used to identify generally the same parts of the aeroplane in the other figures.

An examination of Fig. 8 will make plain the fact that the front edges of the wings in the blank are inclined backward quite sharply, so that the thickened portions produced by the intermediate strips run out or disappear at successive points along the front edge of the wing. In pressing the device to final form, the wings are swung forward (compare Figs. 1 and 8) because of the tapered form assumed by the fuselage. It results that the finished wing tapers in thickness both from front to rear and from fuselage to tip.

As will be clear from an inspection of Figs. 1, 2 and 3, the fuselage portion 21, when pressed to final shape, has a deep U section, open at the top and widest and deepest at the section indicated by the line 25—25 near the junction of the fuselage with the forward portion of the wings 22. From this cross-section, it has a gradual taper in depth and width to the front and rear and terminates at the rear in a single vertical rudder formed by fastening the rudder portions 24 together with adhesive.

The fuselage is weighted and stiffened at its front end by a U-shaped clip 26 of channel section, which is crimped or clamped over the forward margin of the fuselage. This clip 26 carries a finger or hook 27 by which a catapult or other projecting device is connected with the aeroplane. A small cap-like rubber buffer 28 is slipped over the clip 26 and, aside from its utility as a buffer, adds weight to the nose of the aeroplane.

The wings 22, as clearly shown in Figs. 2, 3 and 5, have considerable camber or curvature and a pronounced dihedral angle. The wings preferably are warped rather than ruled surfaces so as to have increased inherent rigidity. Similarly the fuselage is a warped surface, as are its junctions with the wings. These warped surfaces are easily formed by pressure on the dies while the adhesive between laminations is soft, and the form is then permanently fixed by the setting of the adhesive. Naturally such surfaces are less liable to distortion by internal stresses than are ruled surfaces.

The elevators 23 are thickened and stiffened at their front edges by the strip 20. They are shown in the drawings as plane surfaces, but this is not essential as they may be curved or warped, like the wings 22, if desired. Their angle of incidence is a function of the size and balance of the aeroplane and may be either positive, negative or zero according to the particular case.

In case a more finished construction is desired, I apply, as indicated in Figs. 9 and 10, a cover sheet of paper 30 to the top of the entire aeroplane. This closes the top of the fuselage and braces the wings, giving improved flight characteristics and greater strength. When this cover strip 30 is to be used, it is possible, but not necessary, to omit the top sheet 16 from the blank. In either case, the narrow flange 31 is formed on the upper margin of the fuselage forward of the wings and also between the wings and elevators, and to this the cover sheet 30 is caused to adhere.

Once the correct form is established and dies constructed, these aeroplanes may be rapidly and economically manufactured. Tests have shown that they are capable of long gliding flights when projected by a rubber band catapult, and their accurate

form and good mechanical strength make them an attractive toy and advertising novelty.

In the larger sizes, it may be found desirable to add some type of spring propelling motor and propeller. Toy aeroplanes so equipped are familiar to those skilled in the art and the form and arrangement of said mechanism is not a part of said invention. I desire to point out, however, the general adaptability of the present invention to toys of this character for the reason that the fuselage is so constructed as to house and properly support such a mechanism and the nose clip 26 is susceptible of modifications to carry the propeller. Hence, my broader claims are not limited, even by implication, to the glider type of plane.

The process may be carried out in various ways and the article may assume various specifically different forms, but the most important feature is the use of a laminated blank made up of superposed strips of graduated width, and particularly the use of such a blank in such a way that the graduated strips in the wings are skewed, so that the wings taper from fuselage to tip and from front edge to rear. This is favorable to the best weight distribution and to strength, and leads to inexpensive manufacturing methods.

In connection with the feature of weight distribution, it is important also to note that various special results may be secured by a selection of materials for the different laminæ. For example, the use of thin metal, or even of foil, for the narrow lamination 17 at the nose of the plane assists in giving a desirable concentration of weight at this point.

What is claimed is:—

1. The method of constructing toy aeroplanes which consists in preparing a blank composed of laminæ of sheet material in adhesive relation to each other, certain of said laminæ consisting of parallel superposed strips of graduated widths extending perpendicularly to the longitudinal axis of and across forward portions of the wings of the aeroplanes to be formed, and then pressing said blank to form wings and a tapered, channel-shaped fuselage, the form of the fuselage being such that the wings are skewed forward relatively to the fuselage by the pressing operation, whereby said graduated strips are obliquely disposed in the wings of the finished aeroplane.

2. As a new article of manufacture, a toy aeroplane pressed to form from a flat sheet of laminated material, said sheet being graduated in thickness by the use of superposed laminæ of graduated widths.

3. As a new article of manufacture, a toy aeroplane having a tapered U-shaped fuselage and integral wings pressed to form

from a flat sheet of laminated material, said sheet being graduated in thickness by the use of superposed laminæ of graduated widths to cause said wings to taper from the front edge to the rear.

4. As a new article of manufacture, a toy aeroplane having a tapered U-shaped fuselage and integral wings pressed to form from a flat sheet of laminated material, said

10 sheet being graduated in thickness by the use of superposed laminæ of graduated widths to cause said wings to taper toward the tips and rear edges thereof.

5. As a new article of manufacture, a toy 15 aeroplane pressed to form from a flat sheet of laminated material, said sheet being graduated in thickness to give relatively greater mass and strength at the forward portion of the aeroplane, and said aeroplane

20 including a channel-shaped fuselage which tapers toward the rear and terminates in a vertical rudder formed of two portions of the blank folded into face contact with and caused to adhere to each other.

25 6. As a new article of manufacture, a toy aeroplane pressed to form from a flat sheet of material, having a channel-shaped fuselage and wings integral therewith, the fuselage, wings and the junctions of the wings

30 with the fuselage all being warped surfaces, whereby inherent rigidity is had.

7. As a new article of manufacture, a toy

aeroplane comprising in combination a body portion pressed to form from a flat sheet of material, and including a channel-shaped 35 tapered fuselage and wings integral therewith, the fuselage, the wings and the junctions of the wings with the fuselage, all being warped surfaces; and a metal stiffening member clamped upon the forward end of 40 said fuselage and provided with a hook.

8. As a new article of manufacture, a toy aeroplane having a tapered U-shaped fuselage and integral wings pressed to form 45 from a flat sheet of laminated material, said sheet being graduated in thickness by the use of superposed laminæ of graduated widths to cause said wings to taper from the front edge to the rear, said fuselage and wings, and the junctions of the wings with 50 the fuselage, all being warped surfaces.

9. As a new article of manufacture, a toy aeroplane having a tapered U-shaped fuselage and integral wings pressed to form from a flat sheet of laminated material, said 55 sheet being graduated in thickness by the use of superposed laminæ of graduated widths to cause said wings to taper toward the tips and rear edges thereof, said fuselage and wings, and the junctions of the wings 60 with the fuselage, all being warped surfaces.

In testimony whereof I have signed my name to this specification.

FRANK SHORT.
